UNITED STATES PATENT OFFICE

163,155

HOBBYHORSE OR SIMILAR ARTICLE

Minna R. Whitney, Middleburg, Va.

Application August 21, 1950, Serial No. 11,859

Term of patent 14 years

(Cl. D34—15)

To all whom it may concern:

Be it known that I, Minna R. Whitney, a citizen of the United States, residing at Middleburg, in the county of Fauquier and State of Virginia, have invented a new, original, and ornamental Design for a Hobby Horse or Similar Article, of which the following is a specification, reference being had to the accompanying drawing, forming a part hereof.

I claim:

The ornamental design for a hobbyhorse or similar article, as shown.

MINNA R. WHITNEY.
